DESIGN FOR A COMBINED SCABBARD AND CARVING IMPLEMENT SET

Emerson E. Case, Perry, N. Y., assignor to Robeson Cutlery Company, Inc., Perry, N. Y., a corporation of New York

Application December 29, 1945, Serial No. 125,167

Term of patent 14 years

(Cl. D44—29)

To all whom it may concern:

Be it known that I, Emerson E. Case, a citizen of the United States of America, residing in Perry, in the county of Wyoming and State of New York, have invented a new, original, and ornamental Design for a Combined Scabbard and Carving Implement Set, of which the following is a specification, reference being had to the accompanying drawing, forming part thereof.

Fig. 1 is a top plan view of a combined scabbard and carving implement set showing my new design;

Fig. 2 is a side elevational view thereof;

Fig. 3 is an end elevational view thereof, viewed from the left hand ends of Figs. 1 and 2; and

Fig. 4 is an end elevational view thereof, viewed from the right hand ends of Figs. 1 and 2.

I claim:

The ornamental design for a combined scabbard and carving implement set, substantially as shown.
